UNITED STATES PATENT OFFICE.

CHARLES S. STRAYER, OF JOHNSTOWN, PENNSYLVANIA.

SWITCH.

1,408,484.

Specification of Letters Patent. Patented Mar. 7, 1922.

Application filed August 15, 1921. Serial No. 492,339.

To all whom it may concern:

Be it known that I, CHARLES C. STRAYER, a citizen of the United States, residing at Johnstown, in the county of Cambria and State of Pennsylvania, have invented certain new and useful Improvements in Switches, of which the following is a specification.

This invention relates to railway switches and has for its object the provision of means whereby a switch point or tongue may be thrown by the motorman of an approaching car without stopping the car or requiring the motorman to alight. The invention also seeks to provide means whereby the switch point or tongue will be thrown promptly and with certainty and also to provide means whereby water which might tend to collect around the operating parts and freezing so as to prevent the successful operation of the switch may be drained into a sewer or other outlet. The invention also seeks to provide mechanism for the stated purpose which will be simple in the construction and arrangement of its parts and will not be apt to get out of order. The invention is illustrated in the accompanying drawings and will be hereinafter fully set forth.

In the drawings—

30 Figure 1 is a plan view of a switch embodying my invention;

Fig. 2 is a view, partly in side elevation and partly in longitudinal section, of the embodiment of the invention shown in Fig. 1;

35 Fig. 3 is a horizontal section on the line 3—3 of Fig. 2;

Fig. 4 is a transverse section on the line 4—4 of Fig. 2;

40 Fig. 5 is a transverse section on the line 4—5 of Fig. 2.

The track 1 may be of any well-known or preferred construction and will be connected with the side track 2 through a tongue switch and a switch mate 3. The switch is constructed with a recess or chamber 4 in its upper side and the tongue 5 is pivotally mounted at one end of this chamber with its upper surface flush with the upper surface of the switch the car being permitted to continue upon the main track or being deflected onto the side track or branch according to the position of the tongue. Openings 6 are formed through the bottom of the switch in any desired number so as 55 to permit snow or rain to drain into the pit 7 below the same. In the under side

of the tongue 5 is a recess 8 which is engaged by the upstanding arm 9 of a rocker or three-armed lever which is pivoted midway its ends within the pit 7. The arm 9, as shown most clearly in Fig. 5, rises centrally from the lever or rocker 10 which is fulcrumed upon a suitable bracket 11 supported in any convenient manner within the pit. Covers 12 of any convenient or preferred construction are provided over the pit so that it will be normally closed but access may be readily had to the pit when repairs or inspection may be necessary. A sewer or other outlet 13 is provided in the bottom of the pit 7 so that any moisture within the pit may be carried off to any convenient point.

Below the ends of the lever 10, I provide guide pulleys 14 which are mounted upon suitable supports 15 within the pit, and cables or chains 16 are secured to the opposite ends of the lever, as clearly shown. The cables extend downwardly from the ends of the lever and pass under the guide pulleys 14 to guide pulleys 17 which are provided in the pit 7 adjacent one end of a conduit 18 which extends substantially parallel with the main track. From the guide pulleys 17, the cables pass through the conduit 18 to similar guide pulleys 19 at the opposite end of the conduit within a pit 20 which is disposed transversely of the track and is equipped with cover plates 21 corresponding to the covers 12 over the pit 7. From the horizontally disposed pulleys 19, the cables 16 extend inwardly to points under the track where they pass around horizontally disposed guide pulleys 22 mounted in suitable supports upon the front wall of the pit 20, the ends of the cable being then secured in any convenient manner to the depending arms 23 of angle levers which are fulcrumed adjacent the top of the pit and have their upper arms 24 extending rearwardly from their fulcrums and adapted to project through slots 25 in plates 26 disposed in the roadbed between the rails of the track. The upper arms 24 of the angle levers also have their upper surfaces smooth and one of the said lever arms will project above the roadbed and present an inclined surface to an approaching car according to the position of the switch tongue and the three-armed lever engaging the same. 110 Upon reference to Figs. 1 and 4, it will be noted that the angle levers are disposed one

adjacent each track rail at the inner side of the rail, and this arrangement permits the motorman to readily determine which lever should be actuated to set the switch tongue according to the direction in which his car is to proceed. Upon the car are provided plungers or pressers 27 which are normally raised but which may be depressed by the motorman either manually or through other means. In the drawings, I have illustrated, in a conventional manner, a pneumatic motor for depressing these plungers or trippers which motor is governed from the motorman's controller, indicated conventionally at 28.

Upon reference to Fig. 2, it will be noted that the conduit 18 is inclined downwardly from the pit 20 to the pit 7 so that any moisture which may condense therein will readily drain into the pit 7 from which it will escape through the outlet 13 and it will also be noted that a drain pipe 29 is provided extending from the bottom of the pit 20 to the outlet 13 so that any rain or other moisture which may enter the pit 20 will be readily drained therefrom.

From the foregoing description, taken in connection with the accompanying drawings, the operation of the apparatus will be readily understood. As the motorman of an approaching car comes near the switch, he will depress one or the other plunger or tripper 27 and this depressed or lowered plunger or tripper will ride upon the lever arm 24 which is in its path and will depress said arm, thereby swinging the angle lever about its fulcrum so that the arm 23 swings rearwardly and pulls upon the cable 16 attached thereto. The pull upon the cable will be transmitted through the same to the three-armed lever or rocker 10 and said lever will be oscillated or rocked upon its pivot so that the upstanding arm 9 will be swung transversely of the track. Inasmuch as the upper extremity of this arm engages constantly in a socket in the under side of the switch tongue, the tongue will be moved in one or the other direction accordingly as one or the other angle lever is actuated by the corresponding tripper 27. Of course, as one angle lever is depressed, the movement will be transmitted through the attached cable to the corresponding arm or end of the lever 10 and the tongue will be thrown. At the same time, a pull will be exerted in the opposite direction upon the other cable 16 so that one angle lever will always swing upwardly as the other swings downwardly, thereby maintaining a balance between the several parts of the mechanism so that they will move easily and readily under the pres-

sure exerted upon either angle lever by the depressed tripper or plunger. This state of equilibrium existing in the mechanism will also aid in maintaining the cables 16 taut so that they will respond instantly to the actuating force, and, to compensate for any possible stretching of the cable, I prefer to connect them to the angle levers by screw eyes 30 which are threaded through the arms 23 of said levers and may be readily adjusted therein so as to set up the proper tension in the cables.

It will be readily seen that I have provided a mechanism which may be installed at a low cost and which will be operative under all weather conditions. The action of the device is not dependent upon any springs or similar devices which deteriorate through constant use, and the motorman in control of a car approaching the switch may readily determine, before he reaches the switch, whether it is necessary for him to depress either of the plungers or trippers and, of course, he will know which plunger or tripper to depress if it be necessary.

Having thus described the invention, what is claimed as new is:

1. The combination with a railway track, of pits disposed below the track and transversely thereto, a switch tongue pivotally mounted above one of said pits, a rocker in the pit below the switch tongue operatively engaged with said switch tongue, a conduit extending between the pits, angle levers mounted in the upper portion of the pit remote from the switch tongue and each having one arm depending into the pit and another arm projecting through the top of the same, means for selectively actuating said angle levers, and cables passing through the conduit and each attached at one end to the depending arm of an angle lever and at its opposite end to an end of the rocker.

2. The combination with a railway track, of spaced pits below the track and transversely thereto, a switch extending over one of the pits and interposed in the track and having drain openings formed through its bottom, a tongue pivotally mounted on said switch, a rocker in the pit below the switch operatively engaged with said tongue, angle levers mounted in the upper portion of the other pit, means for selectively actuating said angle levers, cables each connecting an angle lever with a corresponding end of the rocker, a drainage outlet from the first-mentioned pit, and a drain pipe connecting the second-mentioned pit with the outlet from the first-mentioned pit.

In testimony whereof I affix my signature.
CHARLES C. STRAYER.
